INTERNAL-COMBUSTION ENGINE

Leonard A. Guaraldi, Somerville, Mass.

Application November 1, 1945, Serial No. 625,999

3 Claims. (Cl. 123—74)

1

This invention relates to improvements in internal combustion engines.

More particularly it relates to two-cycle engines which may be of fractional horse power sizes suitable for driving model airplanes and the like and which, in larger sizes, have general utility for propelling airplanes and vehicles generally, and for supplying motive power wherever a compact, light-weight and efficient engine may be requisite or desirable.

It is an object of the invention to provide an internal combustion engine whose volumetric efficiency ratio is increased as compared with comparable prior engines, and whose crank case is maintained free of explosive gases. According to the invention a relatively highly compressed fuel mixture is released into the outer end of the cylinder thereby to provide an increased volume of fuel mixture in each charge as compared with prior procedures. The cylinder has an inner end wall separating the interiors of the cylinder and crank case, and the incoming fuel mixture is compressed on the inward stroke of the piston and is then by-passed to the outer end of the cylinder. No fuel mixture passes into the crank case, the presence of which in the crank case of prior comparable engines has been a source of great danger, especially in the larger sizes of engines.

Another object is to provide a two-cycle internal combustion engine whose piston has relatively short axial extent and whose cylinder is correspondingly relatively short with rigid closure walls at its opposite ends, and with a rigid shank on the piston extending slidably through the inner end wall of the cylinder and connected outside of the cylinder to a connecting rod.

A further object is to provide a two-cycle internal combustion engine having a cylinder which is closed at each end for relatively high compression of each charge of fuel both on the inward and on the outward stroke of the piston, and having provision for by-passing each compressed newly entered charge of fuel from the inner side of the piston axially of the piston to the extreme outer end of the cylinder.

It is, moreover, my purpose and object generally to improve the structure and operation of two-cycle internal combustion engines.

In the accompanying drawings:

Figure 1 is a side elevation of a two-cycle internal combustion engine embodying features of my invention;

Figure 2 is a cross-sectional view on line 2—2 of Figure 1; and

2

Figure 3 is a view similar to Figure 2 of a modified form.

Referring to the drawings, a two-cycle internal combustion engine is represented which may be considered representative of two-cycle engines generally whether of fractional horse power capacity or made in any of the larger sizes suitable for supplying the motive power for airplanes and other vehicles, for example. While a single cylinder engine is shown, obviously the number of cylinders may be multiplied as may be desired and the cylinders in a plural or multi-cylinder engine may be arranged as desired.

In the drawings, the crank case 10 may be cast with mounting ears 12 projecting at opposite sides, and the ears may have holes 13 therein for reception of bolts or screws for securing the engine as a unit to any suitable and convenient support. The main body of the crank case, as shown, depends below the plane of ears 12 and the usual top opening 14, according to the invention, is closed by a plate 16, in the form of Figs. 1 and 2, or a plate 17, in the form of Fig. 3, which constitutes an inner end wall for the single cylinder 18 which is flanged as at 20 for securing by screws 22 to the crank case, with the plate 16 or 17 intervening between the flange 20 and the crank case and with the screws 20 extending through the plate and securing it as well as the cylinder 18 in place.

Referring to Figs. 1 and 2, the plate 16 has an axial boss 24 projecting into the cylinder chamber 26 and the boss has an axial hole 28 therethrough within which is mounted a bushing 30. A piston 32 is operable within the cylinder chamber 26 and has an axially depending shank 34 rigid thereon extending with sliding fit through the bushing 30. The piston shank 34 has length such that its inner end projects through plate 16 into the interior of the crank case in all positions of the piston, and the inner end of the shank is pivotally connected to one end of a connecting rod 36 whose other end is pivotally connected to crank pin 38 of crank plate 40 which is secured on the end of crank shaft 42. A packing nut 43 preferably engages around the shank 34 at the end of the plate boss 24, it being shown as screwed on the end of the boss.

Piston 32 has short extent axially in cylinder 18 and the cylinder is relatively short. Fuel from any suitable source is conducted through supply conduit 44 to the carburetor indicated generally at 46 whence the fuel mixture enters the cylinder 18 through inlet port 48, on the inner side 55 of the piston, on the latter's outward or com-

pression stroke. According to the invention, however, each newly admitted charge of fuel in cylinder 18 is confined within the cylinder chamber during the major portion of inward movement of piston 32, the plate 16 and packing nut 42 effectively preventing escape into the crank case of any of the newly entered fuel mixture. Hence each new charge becomes relatively highly compressed on the inward stroke, the initial inward movement of the piston closing the inlet port, and final inward movements of the piston uncovering the exhaust outlet 50 and then the outlet port 52 of a by-pass conduit 54 whose inlet port 56 is constantly open at the inner side of piston 32. As soon as the piston moves inward 15 enough to uncover the by-pass port 52, the relatively highly compressed new charge of fuel on the inner side of piston 32 is released into the outer end of cylinder 18 and the pressure of the charge thus entering causes forcible ejection of any exhaust gases remaining from the previous 20 explosion. This driving out of exhaust gases is considerably aided by the deflector part 58 on the piston which directs the incoming charge toward the outer end of the cylinder along the cylinder wall opposite the wall in which exhaust outlet 50 is located, whereby the incoming charge 25 gets behind gases exhausting through outlet 50.

As compared with usual engine construction in which the cylinder is open into the crank case, my present engine attains superior efficiency due to the attainment of a greater compression of each charge of fuel, the greater compression, in turn, being due to the larger amount of fuel mixture entering the outer end of the cylinder under relatively high pressure. Where the inner end of the cylinder is open into the crank case, as in prior art, relatively little compression of the newly entered charge can be effected on the inward stroke of the piston and the charge, when by-passed to the outer end of the cylinder, is less effective for driving out spent gases and less fuel mixture gets into the outer end of the cylinder on each cycle, as compared with the present improved engine in which each charge is relatively 45 highly compressed when by-passed to the outer end of the cylinder.

In the case of plural and multi-cylinder engines, my present construction and manner of operation, eliminates the need for a separate crank case chamber for each cylinder as required in prior comparable engines. Whereas a crank case chamber, sealed with respect to adjacent crank case chambers, has served in effect as a continuation of the associated cylinder in prior comparable engines, my present invention makes it practicable to have a crank case common to all cylinders with no dividing walls or sealed chambers.

In the embodiment shown in Fig. 3, the by-pass from one side to the other of the piston is axially through the piston. In this case the cylinder 60 is mounted as in the previous case, with the plate 17 constituting the inner end wall of the cylinder. The rigid depending shank 62 of piston 64, however, is tubular and its axial passage opens through the outer end of the piston.

The shank extends inward through bushing 66 in the boss 68 of end plate 17 and has its inner end connected at 70 to the connecting rod 72, as in the previously described embodiment.

The outer end wall 74 of cylinder 60 has a rigid depending tubular shank 76 nicely fitting slidably in the tubular shank 62 and terminating short of the plane of the inner end wall 17 of the cyl-

inder. The inner end of tubular shank 76 is closed as at 78.

The fuel supply to the engine of Fig. 3 may be as in the form of Figs. 1 and 2, but the exhaust from cylinder 60 preferably is through an annular series of equally spaced holes 80 in the cylinder walls. With the piston 64 in its position of Fig. 3, and assuming that a fresh charge of fuel has entered the cylinder on the inner side of the piston, the inward stroke of the piston will compress the fresh charge which will be confined within the inner end portion of the cylinder until the piston approaches its inner limit of travel. Nearing its inner limit, the piston first uncovers the annular series of exhaust holes 80 at the outer side of the piston, and then holes 82 in piston shank 62 come into register with holes 84 in shank 76 to permit the compressed charge to enter the axial passage of shank 76 and to pass thence into the outer end of the cylinder through holes 86 in shank 76, close to the outer end wall 74. Hence, as in the previously described case, the compressed charge is by-passed from the inner to the outer end of cylinder 60. However, in the present modification, the new charge enters the outer end of the cylinder at the outer end of the cylinder space and the spent gases exhaust from the cylinder at the inner end of the cylinder space, whereby the entering charge is effectively behind the spent gases for completely exhausting them from the cylinder.

It will be obvious that, in both illustrated embodiments of the invention, the rigid piston shank which is guided axially of the cylinder, eliminates much of the stress which customarily causes uneven frictional wear between the piston and cylinder walls.

I claim as my invention:

1. In an internal combustion engine, a relatively short cylinder having an end wall at each end thereof, a relatively short piston operable in the cylinder for relatively high compression of the same charge of fuel both on the inward and the outward strokes of the piston, a rigid tubular shank on the piston extending through the inner end wall of the cylinder, a rigid shank on the outer end wall of the cylinder extending with sliding fit axially within said tubular shank of the piston, means for admitting a fresh charge of fuel into the cylinder on the inner side of the piston during the outward stroke of the piston whereby said fresh charge is relatively highly compressed by the piston on its inward stroke, there being ports in said shanks whereby said compressed charge is by-passed through the shanks to the outer end of the cylinder during the final inward movement of the piston.

2. In an internal combustion engine, a relatively short cylinder having an end wall at each end thereof, a relatively short piston operable in the cylinder for relatively high compression of the same charge of fuel both on the inward and the outward strokes of the piston, a rigid tubular shank on the piston extending through the inner end wall of the cylinder, a rigid shank on the outer end wall of the cylinder extending with sliding fit axially within said tubular shank of the piston, means for admitting a fresh charge of fuel into the cylinder on the inner side of the piston during the outward stroke of the piston whereby said fresh charge is relatively highly compressed by the piston on its inward stroke, there being ports in said shanks on the inner side of the piston and a port in said end-wall shank close to the outer end wall of the cylinder

whereby said compressed charge is by-passed to the extreme outer end of the cylinder as the piston approaches its inner limit.

3. In an internal combustion engine, a relatively short cylinder having an end wall at each end thereof, a relatively short piston operable in the cylinder for relatively high compression of the same charge of fuel both on the inward and the outward strokes of the piston, a rigid tubular shank on the piston extending through the inner end wall of the cylinder, a rigid shank on the outer end wall of the cylinder extending with sliding fit axially within said tubular shank of the piston, means for admitting a fresh charge of fuel into the cylinder on the inner side of the piston during the outward stroke of the piston whereby said fresh charge is relatively highly compressed by the piston in its inward stroke, an annular series of exhaust ports in the cylinder walls at a location to be uncovered as the piston approaches its inner limit, ports in said shanks on the inner side of the piston adapted to register when the piston approaches its inner limit, there being a port in said end-wall shank close to the outer end wall of the cylinder whereby said com-

10

20

25

pressed charge is by-passed to the extreme outer end of the cylinder during registration of the shank ports at the inner side of the piston, said by-passed charge entering the outer end of the cylinder behind the spent gases therein for effectively driving said spent gases out through said annular series of exhaust ports.
